UNITED STATES PATENT OFFICE

JOSEPH W. J. MASSEAU, OF ST. JOHNS, QUEBEC, CANADA

CLEANING APPARATUS

Application filed June 27, 1932. Serial No. 619,581.

The present invention relates to improvements in cleaning apparatus.

An important object of the invention is the provision of apparatus designed for effectively cleaning the ceilings, walls and various parts of rooms.

A further object of the invention is the provision of cleaning apparatus of the above character designed to enable scrubbing of the ceilings and walls without splashing liquid matter used during the cleaning process about the room.

Another object of the invention is the provision of cleaning apparatus of the above type embodying a container having a cleaning element mounted therein and provided, about the edge of the container, with cushioning and liquid confining means.

Still another object of the invention is the provision of cleaning apparatus of the above type embodying a rotary brushing element and means for selectively rotating the said element.

Other objects and advantages of the invention will become apparent as the description progresses.

In the accompanying drawings forming a part of this specification and in which like reference characters are employed to designate corresponding parts throughout the same:

Figure 1 is a perspective view of the preferred form of invention supported in ceiling cleaning position.

Figure 2 is a side elevational view of the same supported in a wall cleaning position.

Figure 3 is an end view of the apparatus shown at Figure 2.

Figure 4 is a longitudinal sectional view through the cleaner container in ceiling cleaning position.

Figure 5 is a similar view with the container in wall cleaning position.

Figure 6 is a transverse sectional view through the same.

Figure 7 is a transverse section through the casing enclosing the brush operating gearing.

Figure 8 is a fragmentary end view of the socket structure,

Figure 9 is a side view of one of the sockets and the end portion of a tubular casing spaced therefrom,

Figure 10 is a fragmentary longitudinal section through the main support standard, 55

Figure 11 is a similar view through the auxiliary bracing member,

Figure 12 is an enlarged transverse section taken on the line 12—12 of Figure 1,

Figure 13 is a side elevational view of a 60 modified form of the invention in assembly,

Figure 14 is an enlarged longitudinal section through the container,

Figure 15 is a top plan view of the cleaning structure, and 65

Figure 16 is an enlarged fragmentary longitudinal section through the shaft and housing coupling structure.

Referring to Figures 1 to 12 inclusive wherein is illustrated the preferred embodiment of the invention, the numeral 20 generally designates a skeleton base frame having attached to its forward end portion a tubular upstanding standard section 21. Slidably fitted in the section 21 is a complementary extensible standard section 22 provided, at intervals, with apertures 23 to accommodate a transverse pin 24 therein. Disposed about the upper section 22, between the pin 24 and the upper end of the lower tubular section 21, is a coiled compression spring 25 disposed to resiliently support the upper vertical section of the standard. 70 75 80

On the upper end of the standard section 22 is secured a platform 27 having attached to its forward edge an upstanding front plate 28. Rotatably supported in brackets 29 secured to the front plate 28 are a pair of grooved rollers 30. Upon the rear portion of the base frame 20 is secured an upstanding auxiliary standard 32 having fixed on its upper extremity an annular casing 33 housing a train of operating gears. 85

A bracing structure between the auxiliary standard 32 and the platform 27 is provided through the medium of an extensible bracing member 34 having one end secured to the standard 32 and the opposed end connected with the platform. 95

The supporting structure described in the 100

foregoing is particularly adapted to support in ceiling or wall cleaning position a cleaning apparatus embodying an approximately rectangular shaped container 36 open 5 at one end and having attached, to three edges of the opening, cushioned and splash preventing means in the form of relatively narrow elongated bristle containing elements 37. At the fourth edge of the container 10 opening is provided a channel 38 in which is removably disposed a cushioning and absorbing element 39 which may be in the form of an elongated sponge or similar material. In order that splashing of the liquid 15 outside the container be effectually prevented, a baffle 39' is provided which is conveniently secured to the inner wall of the container and the lip of which is disposed adjacent the rotating brush to catch the 20 liquid and return the same to the bottom of the container, (see Figs. 4-5).

Extending transversely through the container and journaled therein is a shaft 41 having detachably secured on its intermediate portion a brush 42 of annular cross section.

Upon one end of the shaft 41 is fixed a worm wheel 43 in mesh with a driving worm 44, the members 43 and 44 being normally 30 enclosed in a detachable casing 45.

The brush 42 is rotated through the medium of a flexible shaft 46, one end of which is connected with the gearing in the casing 33 while the opposed end is provided with a 35 non-circular projection detachably engageable with a socket 47 formed at one end of an extension of the worm 44. Over the flexible shaft 46 is disposed a tubular flexible covering 48 which is fastened to a socket 40 projecting from the casing 33 and to a socket 49 projecting from the casing 45.

The drive gearing within the casing 33 may be manually operated through the medium of a crank 51 or through the medium 45 of an electric motor 52 fastened upon a platform 53 attached to the standard 32, a belt 54 connecting the pulley of the motor with the drive gear of the gear mechanism in the casing 33.

50 When used for cleaning the ceiling, the container is positioned upright upon the elevated platform 27 and securely fastened thereon. The extensible upper standard section 22 is then adjusted so that the upper 55 cushioned edge portion of the container 36 and the sponge 38 are pressed against the ceiling. The brush 42 is then rotated either manually through the medium of the crank 51 or by the motor 52, so as to thoroughly 60 scrub the ceiling and wash the same through the medium of liquid disposed in the container.

When the apparatus is to be employed for washing the wall or vertical partition of a 65 room, the container 36 is suspended upon a

pair of ropes or cables 56 which are trained over the pulleys 30 and auxiliary pulleys 57. One end of each rope 56 is fastened to an angular bracket 58 attached to the container while the opposed end carries a weight 59 70 adapted to counterbalance the weight of the container. To insure proper contact of the narrow brushes and sponge material projecting from the edge of the container opening against the wall, I also contemplate the use of a pole 60 which may be detachably connected with a bracket on the container to insure firm contact with the wall. This supporting arrangement will enable convenient adjustment of the container vertically as well as horizontally so that approximately the entire surface of the wall may be 75 properly cleaned by the rotary brush disposed therein.

In the modified form of the invention 80 shown at Figures 13 to 16 inclusive, I provide a stand 62 supporting an upright standard 63 and secured upon a base frame 64. The base frame 64 is preferably equipped with rollers or other suitable means to enable 85 convenient movement thereof.

On the upper end of the standard 63 is mounted suitable drive gear mechanism enclosed in a housing 65 which, as disclosed in the preferred form, may be manually operated by a crank 66 or through the medium of a motor 67.

The mechanism in the casing 65 drives or rotatably operates a flexible shaft 68 which is disposed in a flexible housing 100 tube 69.

The cleaning structure embodies a frustoconical casing 70 having the inner reduced end provided with a tubular projection 71. The outer enlarged end of the casing 70 is 105 open and provided with an annular marginal ring 72 upon which is secured an annular relatively narrow bristle member or brush 73 projecting outwardly from the casing.

Secured transversely in the casing 70, adjacent the outer end, is a cross bar 74 provided at its centre with a bearing forming aperture through which is rotatably extended a rigid shaft 75. On the upper end of the shaft 75 is fixed an annular plate or disk 75 having attached to and projecting outwardly from the outer base brush forming bristles 77. The inner portion of the shaft 75 extends through the tubular projection 71 and is provided with a tapered non-circular extension 78 engageable with a corresponding recess in a coupling 79. To the inner end of the coupling 79 is connected a flexible shaft 68 joined by the coupling 125 with the rigid shaft 75.

This form of the invention is likewise adapted for cleaning the ceilings as well as the walls of a building and, due to its relatively light cleaning structure, can be 130

readily adjusted into cleaning arrangement as found desirable.

Having thus described my invention, I claim:

5 In cleaning apparatus for ceilings, walls and the like, a liquid containing casing open at one end, a rotatable brush mounted in the casing adjacent one wall of the casing and the bristles of said brush projecting 10 outwardly beyond the plane of the casing opening, bristles disposed at the edge of the casing about the opening for liquid sealing purposes, a strip of absorbent material 15 removably secured to the edge portion of the opening immediately adjacent the brush, to

absorb and return to the casing liquid spattered by the brush, a vertically adjustable support standard, a platform on the upper end of the standard for supporting the container thereon for ceiling cleaning purposes, means on the platform for removably securing the casing thereon, means associated with the platform and casing for supporting the casing in platform-detached position for wall cleaning purposes, and flexible 70 shaft means connecting the rotary brush to a motive power source attached to the standard. 75
